C. L E R. NEVIN

FIRE EXTINGUISHER

Filed July 29, 1926

Patented Nov. 1, 1927.

1,647,880

UNITED STATES PATENT OFFICE.

CHESTER LE ROY NEVIN, OF HONOLULU, TERRITORY OF HAWAII.

FIRE EXTINGUISHER.

Application filed July 29, 1926. Serial No. 125,785.

The present invention is concerned with the provision of a fire extinguisher in the nature of a metal container filled with a fire extinguishing chemical which automatically discharges under pressure when the container is inverted from its normal position.

An object of the invention is to provide a container which will effectively prevent leakage of the chemical at all times, and a valve mechanism for the container which is positive in operation to release the chemical, when the container is inverted.

A further object of the invention is to provide a fire extinguisher of simple, practical construction, which will be rugged, durable and efficient in use, which may be manufactured with comparative economy, which may be readily charged, conveniently manipulated, and which will require the use of no special supporting brackets for securing it in its normal inoperative position.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view in longitudinal section through a fire extinguisher embodying the present invention.

Fig. 2 is a similar view showing the extinguisher inverted and in proper position for discharge of the contents thereof.

Fig. 3 is a transverse sectional view on the line 3—3 of Fig. 2.

Fig. 4 is a fragmentary sectional detail showing a modification in which a soldered break plug is substituted for the cap 14.

For the convenience of description I shall call the bottom of the container—the part which constitutes the lower end thereof when the container is in its normal inoperative position shown in Fig. 1.

The container comprises a metal shell 10 of cylindrical or other appropriate cross sectional shape. The bottom 11 of the shell is formed with a relatively small opening 12 communicating with a nozzle 13 secured beneath the bottom of the container and normally closed by a screw cap 14 which presses a sealing disc of lead or other appropriate material 15 against the outlet end of the nozzle. The open upper end of the container

10 is closed by a cap 16 welded or brazed to the container and formed with a threaded nipple 17 receiving a threaded plug 18. The plug is formed at its upper end with a 60 knurled head 19 normally clamping a lead sealing gasket 20 against the outer face of the nipple 17. The container 10 may be conveniently supported upon a tripod consisting of three legs 21 connected at their upper ends to a split band 22 clamped in position upon the lower end of the container by a clamping screw 23 passed through aligned apertured ears 24 at the end of the band. A handle member 25 straddling the top of 70 the container may be carried by a similar split band 26 which engages under the flange 16^a of the cover 16, and is held against upward movement.

Rising centrally of the container is a pipe 27, the lower closed end 28 of which is welded or otherwise secured to the bottom 11 of the container and formed with an opening 29 registering with the opening 12 in the container bottom. Pipe 27 terminates below the cover 16. Mounted in the pipe is a relatively heavy plunger element 30. This plunger element is of slightly less diameter than the pipe to provide an annular liquid space between its outer surface and the inner surface of the pipe. Plunger 30 is formed at one end with a suitable valve member 31 coacting with the valve seat defined by the opening 29 in the bottom 28 of the pipe 27.

As illustrated the extension 31 is of approximately conical or needle shape, but it is to be understood that various types of gravity operated valves might be used in this connection. Plunger 30 also terminates 95 short of the upper end of the container and has limited axial movement within the pipe 27 sufficient to permit withdrawal of the valve 31 from its seat 29 before the plunger engages the plug 18.

Plunger 30 may be provided with a screw-driver receiving slot 35 in its upper end in order to permit the valve 31 to be ground upon its seat.

In charging the extinguisher, the plug 18 is removed and the container is about three-quarters filled with a suitable liquid chemical, such for instance as carbon tetrachloride. The plug 18 is then replaced. Cap 14 is removed, and the nozzle 13 placed in connection with a suitable source of compressed air which flows up around the plunger 30 and

into the main chamber of the container. Cap 14 is then replaced, and the device is ready for operation.

In case of fire, the cap 14 is removed and 5 the container manually grasped and inverted as shown in Fig. 2. It will be noted in this figure that the plunger 30 has gravitationally dropped, resting on the plug 18 and unseating the valve 31. Consequently 10 the fluid fire extinguishing chemical is ejected by the air pressure through the nozzle 18, as will be readily understood.

If desired, the plug 18 with its associated 15 parts 17, 19 and 20 may be dispensed with, and the filling done under pressure through the nozzle 13.

In Fig. 4 I have illustrated a slight modification wherein the cap 14 is eliminated and a handle member 40 soldered to the nozzle 13 by a break solder joint indicated at 41. With this form of the invention, release of 20 the contents of the extinguisher may be effected by grasping the handle 4, and forcibly swinging or twisting it to break the 25 solder joint.

Various changes and alterations might be made in the general form and arrangement 30 of parts described without departing from the invention. Hence I do not wish to limit myself to the details set forth, but shall consider myself at liberty to make such changes and alterations as fairly fall within the spirit 35 and scope of the appended claims.

I claim:

35 1. A fire extinguisher including a casing having a discharge opening in its bottom and a filling opening in its top, a discharge nozzle connected to the discharge opening and a gravity operated valve element normally closing said discharge opening, said

valve element including a relatively heavy elongated bar guided for limited gravitational axial shifting movement in the casing, the guide means including a tube of greater internal diameter than the external diameter 45 of the bar.

2. A fire extinguisher including a casing having a discharge opening in its bottom and a filling opening in its top, a discharge nozzle connected to the discharge opening and a gravity operated valve element normally closing said discharge opening, said valve element including a relatively heavy elongated bar guided for limited gravitational axial shifting movement in the casing, the 50 guide means including a tube of greater internal diameter than the external diameter of the bar, said tube being secured to the bottom of the casing and terminating below 55 the top of the casing.

3. A fire extinguisher including a casing having a discharge opening in its bottom and a filling opening in its top, a discharge nozzle connected to the discharge opening and a gravity operated valve element normally closing said discharge opening, said valve element including a relatively heavy elongated bar guided for limited gravitational axial shifting movement in the casing, the guide means including a tube of greater 60 internal diameter than the external diameter of the bar and having a closed lower end, said tube being secured to the bottom of the casing and terminating below 65 the top of the casing, the closed lower end of the tube having an opening therein registering with the discharge opening in the 70 container bottom.

CHESTER LE ROY NEVIN.
